UNITED STATES PATENT OFFICE.

HENRY L. FERRIS, OF HARVARD, ILLINOIS, ASSIGNOR TO HUNT, HELM, FERRIS & COMPANY, OF HARVARD, ILLINOIS, A CORPORATION OF ILLINOIS.

DOOR-HANGER TRACK.

1,027,713.

Specification of Letters Patent.

Patented May 28, 1912.

Application filed November 29, 1909. Serial No. 530,415.

To all whom it may concern:

Be it known that I, HENRY L. FERRIS, a citizen of the United States, residing at Harvard, in the county of McHenry and 5 State of Illinois, have invented a new and useful Improvement in Door-Hanger Tracks, of which the following is a specification.

My invention relates to new and useful 10 improvements in door-hanger tracks, and is fully described and explained in the specification and shown in the accompanying drawing, in which—

Figure 1 is a front elevation of the length 15 of my improved track; Fig. 2 is a transverse section through the same; Fig. 3 is a detailed front elevation, some of the parts being broken away to show the construction; Fig. 4 is a perspective view of one of 20 the coupling and alining members; and Fig. 5 is a similar view of the adjacent coupling or lining member adapted to coöperate therewith.

Referring to the drawings, A is a substantially semi-cylindrical member which constitutes the rear portion of the track. In front of the member A is disposed a second member of sheet-metal comprising a semi-cylindrical portion B, an outwardly bent 25 shoulder b, adapted to seat the forward edge of the member A, a substantially horizontal web b¹, adapted to overlie and be fastened to a portion of the member A, a diagonally-disposed shield-portion B¹ and a 30 vertical portion b² terminating in a backwardly-turned lip b³. The two members of which the track is composed are so disposed with reference to each other that together 35 they form a substantially cylindrical hollow track slotted at the bottom, the track being 40 adapted to receive a door-hanger within it, the door-engaging portion of the hanger extending out through the slot, provided between the lower edges of the two members 45 of the track, to engage the door.

It is preferred to make the track in the form of short sections by reason of the numerous advantages presented by such 50 method of manufacture and when so made an accurate coupling and alining device is especially desirable, although even when the track is made in long lengths such coupling and alining devices are useful. Such a coupling and alining device is illustrated in the 55 drawing, where it will be seen that each sec-

tion of the track has attached to one of its ends a coupling-member C and to the opposite end a coupling-member D. The coupling-members are made in the form of vertical plates of sheet-metal which extend upward substantially from the intersection of the horizontal diameter of the track with its rear wall secured to the upper edge of the vertical portion b² of the forward member of the track, the coupling and alining members being riveted to the member A, in the manner illustrated, and held in proper engagement at their upper ends by being perforated to receive the bolts, screws or other devices by which the track is supported. The couplings, or alining members, D are provided with forwardly-projecting studs d and the alining-members C are provided with laterally-projecting slotted ears e, bent forward out of the plane of the alining-members, so as to overlie the alining-members D and adapted to engage the studs d thereon.

The method of assembling the track will be perfectly obvious from the drawings, 80 from which it will be seen that one section is put up in the proper line, in the obvious way, the second section engaged therewith by means of the alining-members and then secured in place itself to furnish the starting-point for a third section. The track is particularly advantageous because of its strength, simplicity and cheapness in construction, and furthermore by reason of the fact that in an exceedingly cheap and simple form a track is provided, and a deck, or 85 sheltering web, is provided extending from the track to the wall of the structure so as to prevent entirely the passage of dust, and, more especially, rain-water, behind the door. 90

It will be evident, of course, that the particular form of track, when viewed in cross-section, is subject to great variations, and, as far as certain features of my invention are concerned, the coupling mechanism is not of 100 importance.

I realize that considerable variation is possible in the details of construction of my improved device, without departing from the spirit of my invention, and I do not intend, 105 therefore, to limit myself to the specific form herein shown and described.

What I claim as new and desire to secure by Letters Patent is—

1. A track section having a semi-cylindri- 110

- cal rear portion and a front portion, the lower part of which is semi-cylindrical, said semi-cylindrical portions facing each other to form a hollow and having their lower edges spaced apart to form a slot, the front portion having an integral extension running diagonally up and back over the rear portion to the wall of the building to shield and cover the rear portion and being riveted to the upper edge of the rear portion, and means connecting and bracing the center of the rear portion with the upper edge of the shield.
2. A track section comprising front and rear semi-cylindrical portions facing each other with their lower edges spaced apart to form a slot, said parts being riveted together at the top, and the front portion being extended backward and diagonally upward to form a shield.
3. A series of track sections each having

a semi-cylindrical rear portion, and a front portion, the lower part of which is semi-cylindrical, said semi-cylindrical portions facing each other to form a cylindrical hollow track and having their lower edges spaced apart to form a slot, the front portion having an integral extension running diagonally up and back over the rear portion to the wall of the building to shield and cover the rear portion, and vertical members connecting the upper part of said extension with the center of the rear portion and notched ears on the vertical members at one end of each section and studs on the vertical members at the other ends thereof to engage said notched ears.

HENRY L. FERRIS.
